UNITED STATES PATENT OFFICE.

ROGER M. HOPKINS, OF COLO, IOWA.

KEROSENE-OIL BURNER.

Application filed February 20, 1924. Serial No. 694,065.

This invention relates to kerosene oil burners and it consists in the novel features and arrangement of the parts as hereinafter described and claimed.

An object of the invention is to provide a burner of the character stated which is of simple structure and which includes means for pumping a blast of air through a nozzle member and mixing the blast with a stream 10 of oil in the nozzle member in an atomized condition. This mixture of air and oil is directed into the body of the burner proper where it is ignited. As the mixture moves from the nozzle to the body of the burner proper, it draws with it a volume of atmospheric air which supplies additional oxygen to the mixture and within the body of the burner proper and this additional supply of the oxygen facilitates combustion within the 20 body of the burner proper and produces an intensely hot flame therein.

Means are provided for recovering any unconsumed oil which may accumulate in the body of the burner proper and this unconsumed or overflow supply of oil is returned 25 to the source which supplies the oil to the nozzle in the first instance.

In the accompanying drawing:

Figure 1 is a plan view of the kerosene 30 oil burner.

Figure 2 is a side elevation of the same with parts broken away and parts shown in section.

Figure 3 is a vertical sectional view of 35 the nozzle structure of the burner.

The burner structure includes a hollow cone-shaped circular body 1 having an air intake 2 communicating with the interior thereof and through the side thereof, the 40 same being tangentially disposed with relation to the circular configuration of the body 1. A fan casing 3 is located adjacent the inlet end of the intake 2 and a pipe 4 communicates at one end with the interior of the 45 casing 3 and the opposite end of the pipe 4 is disposed centrally at the inlet end of the nipple 2. The pipe 4 is smaller than the intake 2, thereby providing space between the side and the adjacent end of the pipe 4 50 and the intake. A fan 5 is journaled for rotation in the casing 3 and its shaft 6 is an extension of, or is coincident with, the shaft of a motor 7. A pulley 8 is mounted upon the shaft of the motor 7 and is alined with a pulley 9 mounted upon the shaft of a 55 pump 10. A belt 11 is trained around the

pulleys 8 and 9 and is adapted to transmit rotary movement from the shaft of the motor 7 to the shaft of the pump 10. The casing of the pump 10 is connected by means of 60 a pipe 12 with a tank 13. A pipe 14 is also connected with the casing of the pump 10 and extends adjacent the intake 2, passes through the side of the intake and is connected at its other end with a nozzle disposed centrally within the intake 2 and at a point spaced from the point of juncture between the latter 2 and the body 1. The reduced discharge outlet end 16 of the outer 65 part 15 of the nozzle is disposed toward the body 1. An inner part 17 is located interiorly of the part 15 with its walls spaced from the walls of the latter and the reduced outlet end 18 is alined with the corresponding end 16 of the part 15. The air pipe 14 connects with the inner end of the part 17. The latter is greater in diameter than the 70 pipe 14.

An oil tank 19 is connected by means of 80 a pipe 20 with the interior of the part 15 of the nozzle, the pipe 20 penetrating the side thereof at a point between the ends of the same. A pipe 21 may be provided for supplying oil to the tank 19. A return pipe 22 connects at one end with the bottom of the 85 body 1 and connects at its other end with a collecting tank 23. A pipe 24 connects the tank 23 with the oil supply tank 19.

The operation of the burner is as follows: The motor 7 is started, and the fan 5 is 90 rotated, and a blast of air is discharged through the pipe 14 into the intake 2. This blast carries with it, air from the atmosphere which enters the intake through the space between its wall and the wall of the pipe 95 4 at the adjacent ends of these parts. This blast, together with the air which is drawn in, moves over and along the mixing nozzle and enters the body 1 of the burner. At the same time, the motor 7 actuates the 100 pump 10 and air is pumped from the reservoir or tank 13 through the pipe 14 into the nozzle part 17. The blast of air is discharged from the outlet opening 18 into the end portion of the part 15 and creates a partial vacuum within the nozzle. This vacuum draws the oil through the pipe 20 from the tank 19 up into the body of the nozzle and the oil which is accumulated therein is sprayed 105 through the outlet opening 16 into the blast of air, hereinbefore described, which is moving through the intake 2. The mixture is 110

2
ignited within the body 1 and produces an intensely hot flame. In that the currents of air move at slow velocity through the pipes, nozzle, intake, the burner is quiet in its operation and roaring noises are eliminated.

5 Any overflow of the oil which may accumulate in the body 1, flows down through the pipe 22 into the tank 23 and from the tank 23, the said oil may be drawn by the 10 suction established through the pipe 24 into the tank 19 from which point it is again led to the nozzle 15 as hereinbefore described, and is reintroduced into the body of the burner 1.

15 While it has been stated that the burner is adapted to be used for consuming kerosene, it may in fact be used to advantage for burning a mixture of fifty per cent kerosene and fifty per cent waste oil drained from the 20 crank casing of an automobile. In fact the burner may be used to advantage for utilizing as a fuel any other oil of a lower grade than kerosene. In further explanation of the operation of the device, it may be stated that 25 any unconsumed oil from the burner body 1 may pass through the pipe 22 to the tank 23 and any overflow from the chamber 19 may pass through the pipe 24 to the chamber 23. The chamber 23 may contain a float 30 and as the level of the oil in the chamber 23 rises an electric circuit is broken at the contact 25 and thereby serving as a signal and stopping the operation of the burner. The

object of such provision is to provide a safe guard to prevent the burner from operating 35 if the oil is not being consumed or if the needle valve in the float chamber 19 is not operating properly.

Having described the invention, what is 40 claimed is:

In a fuel feed system of the class described, in combination, a head provided with an air conducting nipple, a pipe arranged to deliver a blast of air into the nipple at the receiving end of said nipple, 45 said pipe being less in diameter than the diameter of the nipple and having its wall spaced from the wall of the nipple at the receiving end of the nipple, means for forcing a blast of air through the pipe into the 50 nipple in order that atmospheric air is drawn into the nipple through the space between the pipe and the nipple, an oil atomizing and projecting nozzle located within the nipple and having its discharge end disposed toward 55 said head, means for leading oil into said nozzle, means for discharging a blast of air into the nozzle for atomizing and spraying the oils into the air blasts passing through said nipples, and an oil return pipe 60 connected with the burner head and with the oil supply means for said nozzle, the air blast leading to said nozzle, serving to aid in drawing the oil through said return pipe.

In testimony whereof I affix my signature.
ROGER M. HOPKINS.
